MASS SPECTROMETER ION SOURCE

Frederick L. Reynolds, San Francisco, Calif., assignor to the United States of America as represented by the United States Atomic Energy Commission

Application December 29, 1949, Serial No. 135,701

11 Claims. (Cl. 250—41.9)

1

The present invention relates to ion source mechanisms, and more particularly to an ion source mechanism adapted to effectively ionize minute samples. More specifically the invention provides apparatus for the rapid insertion and ionization of samples, which is particularly advantageous, for example in the analysis of unstable elements and isotopes.

The principles of electromagnetic mass spectrometry have long been understood and diligently explored by many workers. Within recent years this art has found wide application in the analysis of gaseous mixtures and has also been found to be very advantageous in the analysis of minute samples which are not easily analyzed by chemical methods. In line with these advantages attempts have been made to employ electromagnetic mass spectrometry in the analysis of the end products of bombardment specimens and the like. Modern particle accelerators and like equipment have provided means to change the structure of atoms and molecules and thereby promise to afford an insight into atomic physics; however, difficulty has been encountered in the analysis of the materials produced by such apparatus. Many of the materials produced by bombardment of samples with high energy particles have a very transitory nature and decay rapidly into other more common elements, and in order to accurately determine and identify the products of such bombardment it is necessary to analyze the samples very quickly.

As will be acknowledged by those familiar with the art of electromagnetic mass spectrometry, there is an appreciable delay from the time that a sample (other than gaseous) is inserted in a conventional mass spectrometer until an analysis is obtained. It is to overcome this limitation that the present invention was conceived, although it will, of course, be apparent that the applicability of the invention is in no wise limited to cooperation with an analyzing mass spectrometer, but instead the scope of the invention includes all uses to which an ion source may be put.

It is therefore an object of the present invention to provide a method and means of rapidly analyzing a sample in a mass spectrometer.

Another object of the invention is to provide a method and means of rapidly inserting and removing the ion source mechanism of a mass

2

spectrometer without affecting the vacuum thereof.

Another object of the invention is to provide an ion source mechanism capable of easy and rapid insertion in a mass spectrometer.

Still another object of the invention is to provide a method and means for rapidly and easily inserting a sample in an ion source mechanism.

Yet another object of the invention is to provide an ion source mechanism having a preadjusted removable filament for the rapid handling of ionizable samples.

A still further object of the invention is to provide a method and means of determining the efficiency of removal of ions from an ion source mechanism.

Further objects and advantages of the invention will become apparent from a consideration of the following description and accompanying drawings, of which

Figure 1 is a vertical sectional view of the ion source proper and ion source box taken along the line 1—1 of Fig. 2;

Fig. 2 is a plan view of the ion source proper as viewed from the left of Fig. 1;

Fig. 3 is a partially exploded, perspective view of the ion source proper; and

Fig. 4 is a schematic wiring diagram for the ion source.

Considering the invention in general, it will be noted from the drawings that the ion source proper 50 includes a thermal ion production means 51 and a plate assembly 52 comprising a plurality of parallel spaced plates having openings therethrough in line with the ion production means. The source proper is provided with a number of prongs which mate into cooperating apertures in an ion source support assembly in the manner of a socket thereby providing means for the rapid removal and insertion of the ion source proper 50 in the ion source box 30 of an electromagnetic mass separator. Also the ion production means 51 is provided with preadjusting means and a socket connection to the ion source plate assembly 52 whereby the time required to initiate operation of the separator following insertion of the sample to be ionized is minimized.

Referring more specifically to Figs. 1, 2, and 3, it may be noted that the plate assembly 52 com-

prises a plurality of plates secured together by suitable mounting studs 1 and spaced apart by insulating spacers 2 immediately surrounding the studs 1. In order to prevent electrical connection between the plates of the plate assembly 52, the studs 1 may advantageously comprise a metallic central member threaded on each end and surrounded by an insulating material, as shown, or may comprise an insulating member having threads formed directly on each end. The studs pass through the plates of the plate assembly 52 and tie it together by means of nuts secured to each end of the studs 1 and bearing on a face plate 3 at one end of the studs and a collar or washer at the other end of the studs to hold the end spacers in position as shown. The face plate 3 has a central circular opening 4 therein and four spaced prongs 6 normal to the surface of the plate and rigidly attached thereto. A focusing plate 7 abuts the rear wall of face plate 3 and has a central slit 8 formed therein within the area of the opening 4 in face plate 3. Directly behind focusing plate 7 and separated therefrom is an accelerating plate 9 having a slit 11 provided therein in alignment with the slit 8 of plate 7. Behind the accelerating plate 9 and in close proximity therewith is situated a protection plate 12 having a large central opening. Spaced behind the protection plate 12 is a thermal plate 13 having a central slot 14 in alignment with the slits 8 and 11 of plates 7 and 9, respectively.

The ion production means 51 is separably mounted on the rear of the plate assembly 52 by means of four prongs 15 which are rigidly attached to the thermal plate 13 and extend outwardly from the plate assembly. Prongs 15 mate with suitable bores in the ends of spacing means such as the four adjusting screws 16 which have threaded mounting in a filament holder plate 17 and thereby determine the spacing between the latter and the thermal plate 13. Also attached to thermal plate 13 is a pair of bolts 18 which pass through openings in the filament holder plate 17 and maintain said plates in operative position by suitable means such as nuts threadably engaging the bolts 18 and bearing upon the back of the filament holder plate 17, as will be understood from Fig. 1. A filament such as wire 21 may be positioned in the slot 14 in thermal plate 13 through correct mounting on plate 17 which is accomplished preferably by the use of a pair of metal-glass supporting insulator connectors 19 which extend through the filament holder plate 17. Insulator connectors 19 serve to support the filament 21 in a definite and fixed position upon the filament holder plate 17 and provide a means of connecting the filament to an external power source while maintaining an insulated relationship between the filament 21 and the filament holder plate 17.

As may be noted from Fig. 1, the ion source proper 50 is adapted to be contained within an ion source box 30. The latter has an opening in one wall thereof which is closed by a vacuum pipe 31, the outer end of which may be connected to a vacuum system (not shown). An opening 32 is provided in the front wall of the source box 30 and about this opening and on the inner face of such wall is provided an annular socket plate 33 secured in any suitable manner thereto, as by the cap screws 35. For facilitating union with the ion source face plate 3 the socket plate 33 is provided with four spaced holes 36 which match the size and position of the four prongs 6

of the former. As will be readily apparent, the ion source proper 50 is assembled with the ion source box 30 by inserting the prongs 6 in the holes 36, the outer rim of the face plate 3 resting upon an inwardly disposed shoulder of an adjusting nut 37 which threadably engages the outer circumference of socket plate 33. The spacing between the face plate 3 and the front wall of the apertured source box is determined by the setting of adjusting nut 37. The ion source proper 50 is locked in adjusted position by means of a clamping nut 38 which surrounds the ion source proper, abuts the rear face of the outer rim portion of the face plate 3, and threadably engages an inner circumference of adjusting nut 37. One wall 39 of the ion source box 30 is preferably removable, as shown, to permit easy access to the ion source proper and such a wall is maintained in vacuum tight contact with source box 30 by suitable means such as bolts 40 and suitable sealing means, such as a ring gasket.

It will, of course, be appreciated that in addition to the above-noted means for facilitating rapid removal and insertion of the ion source, the mass separator apparatus with which the ion source cooperates may advantageously be equipped with means to isolate the remainder of the system under vacuum from the ion source box. Such means (not shown) may comprise vacuum tight gates between the vacuum pumping system and the source box, and between the mass separator chamber and the ion source box. Also, it may be advantageous, although not necessary, to provide a special pumping arrangement to rapidly evacuate the ion source box and at the same time maintain the vacuum on the remainder of the system. The above-noted provisions in the vacuum system serve to further accentuate the advantages of the present invention which permit a rapid analysis of the sample following insertion of the ion source, inasmuch as the time required to obtain proper vacuum conditions pre-requisite to operation of a mass spectrometer is minimized.

Before considering the operation of the invention, it is of importance to note the electrical connections and potentials associated with the elements of the source, and in this respect attention is invited to Fig. 4. The filament 21, which is shown withdrawn from its operating position for ease of illustration, is connected across an appropriate power supply 41. It will, of course, be appreciated that numerous types of supply components would be suitable for supplying the potentials applied to the individual plates of the plate assembly, batteries only being illustrated for reasons of simplicity and convenience. By means of batteries 42 and 43, respectively, the accelerating plate 9 and the protection plate 12 are each maintained at a large negative potential with respect to the filament 21 and the thermal plate 13 which may be grounded. The focusing plate 7 may be maintained at a lesser negative potential than the accelerating plate 9 by means of a battery 44. A current measuring device, such as a galvanometer G or similar instrument, is connected between the thermal plate 13 and the accelerating plate 9 to indicate the current flow therebetween for the reasons set forth in detail below.

With the physical structure of the invention and the electrical connections of the individual elements thereof in mind, the operation of the invention may now be considered. Prior to an

analysis of a sample the filament is properly positioned in the assembly. This is accomplished by rotation of adjusting screws 16 until, with the ion production means 51 in place, the filament wire is symmetrically disposed within the slot 14 of the thermal plate 13 and is flush with the front surface thereof. The proper disposition of the ion source proper 50 within the ion source box 30 is then obtained by rotation of the adjusting nut 37 until, with the face plate 3 in contact therewith, the distance from the front of the thermal plate 13 to the front opening 32 of the ion source box is the proper spacing for proper operation of the particular electromagnetic separator with which the ion source is co-operating.

Following the above adjustments the ion source is ready for operation. The ion production means 51 is removed from the ion source proper 50 and the sample to be analyzed is placed on the filament wire 21. In many cases the sample will be in solution and thus the filament is merely dipped in the solution. The ion producing means is then placed in position on the ion source plate assembly 52 by slipping the prongs 15 into the bores in the enlarged ends of the four adjusting screws 16. The ion production means 51 is secured in this position by placing the nuts on the bolts 18 and tightening them until they bear on the filament holder plate 17. Following this operation the filament is in proper position with respect to the thermal plate 13 because of the previous adjustment of the adjusting screws 16. The ion source proper 50 is then plugged into the ion source box assembly by inserting prongs 6 into holes 36. The ion source is secured in this position by engaging the clamping nut 38 and tightening it onto the adjusting nut 37 until the face plate 3 is tightly secured between the two. In this position the filament 21 is properly spaced for operation because of the previous adjustment of the adjusting nut 37. The cover 30 is then placed on the source box 30 and secured in vacuum tight relation therewith by tightening the nuts on bolts 40. Following evacuation of the ion source box the apparatus is in proper condition to ionize the sample for analysis.

Ionization of the sample is produced by heating of the filament 21 as a result of current passing therethrough from the current source 41. Ions produced by heating the sample are attracted toward the accelerating plate 9 as a result of the potential difference existing between the accelerating plate 9 and the filament 21 or thermal plate 13. The ions pass through the large aperture in the protection plate 12 and by virtue of their induced velocity pass through the slot 11 in the accelerating plate 9 and on through the aligned openings in the focusing plate 7 and the face plate 3 and through the openings in the socket plate 33 and ion source box wall into the spectrometer chamber (not shown). The focusing plate is maintained at a lesser negative potential and thus acts to constrict the ion beam passing through the slot 8 therein, thereby focusing the beam.

Upon completion of the analysis of a sample, the ion source proper may be easily removed from the ion source box and the ion producing means separated from the remainder of the ion source proper. The apparatus is then ready for another sample. As may be noted from the above description of operation, only two simple steps are necessary to place the ion source in position for operation. The first, following the placement

of the sample upon the filament, is to slip the ion production means 51 upon the ion source plate assembly 52 and secure it there; and the second is to plug in the ion source proper 50 in the ion source box and tighten the clamping nut 38. The operation consumes at most a few seconds and the entire operation following production of the sample to complete ionization and analysis requires but an extremely short period.

10 The advantages of this rapid analysis will, of course, be appreciated in connection with the analysis of radioactive samples containing isotopes having very short half lives; however, advantage also lies in the rapid analysis of ordinary stable isotopes in that many experiments are facilitated and the time required for the compilation of extensive separation data materially decreased.

As may be noted from the above description, 20 the sample ionized in the source is quite small and thus it is important for the separator to have a high efficiency; that is, the ratio of ions impinging upon the receiver to ions formed at the source must be maximized. The losses in 25 the source may be determined by the current measuring apparatus G connected between the thermal plate 13 and the accelerating plate 9 in series with power supply 42 as shown; the current flow between the thermal plate 13 and 30 the accelerating plate 9 being an indication of the amount of ions impinging the accelerating plate. It is to be noted, however, that a large potential difference exists between the thermal plate and the accelerating plate, and thus a certain amount of leakage may occur across the 35 surface of the insulating spacers 2 which would be recorded on the meter. In order to prevent this type of error the protection plate 12 is inserted in the ion source plate assembly. The 40 protection plate 12 is maintained at approximately the same potential as the accelerating plate 9 and thus any leakage across the spacer surface would occur between the thermal plate and the protection plate. The acceleration plate 9 is thereby protected from current leakage, and thus the meter accurately indicates the quantity 45 of ions impinging upon the accelerating plate.

Only one type of ion production means has been described; however, it will be apparent to 50 those skilled in the art that other types are adaptable to the same principles set forth above without departing from the spirit of the invention. A bombardment type source may be employed and is advantageous in connection with 55 the analysis of extremely small samples in that a stronger signal may be produced; however, this type of ion producing means provides a contaminated beam as a result of the complex ions produced by the bombardment. Thus the type 60 of ion producing means employed in any particular analysis is dependent upon the circumstances of that analysis, with any one of a number of well-known types of ion producing means being adaptable for use in accordance with the 65 principles of the present invention.

It will, of course, be appreciated by those skilled 70 in the art that many variations and modifications are possible within the spirit and scope of the invention, and thus the invention is not to be limited to the exact details disclosed except as may be defined in the following claims.

What is claimed is:

1. In an ion source mechanism the combination comprising a plate assembly including means for accelerating and focusing ions, and ion pro-

ducing means, said plate assembly and said ion producing means including cooperating socket elements whereby said ion producing means is adapted to plug into said plate assembly for ease and rapidity of assembly and disassembly.

2. In an ion source mechanism the combination comprising a plate assembly adapted to accelerate and focus ions, ion producing means, and adjustable spacing means connecting said plate assembly and said ion producing means, said spacing means comprising a socket assembly whereby said ion producing means and said plate assembly may be rapidly connected and disconnected.

3. In an ion source mechanism the combination comprising a plate assembly adapted to expel ions from the source, ion producing means, pre-adjusting means interconnecting said plate assembly and said ion producing means whereby the spacing therebetween is predetermined, said preadjusting means slidably engaging said plate assembly whereby connection of said ion producing means and said plate assembly is facilitated, and locking means secured to said plate assembly and engaging said ion producing means whereby said predetermined spacing therebetween may be preserved.

4. In an ion source mechanism the combination comprising a plate assembly adapted to expel ions from said source and having one element of a socket connection secured thereto, ion producing means, a plurality of adjustable spacers connecting said plate assembly and said ion producing means, said spacers comprising one element of a socket connection mating with said plate assembly socket element whereby said ion producing means and said plate assembly may be assembled and disassembled without readjustment of the spacing therebetween.

5. In an ion source mechanism the combination comprising a plate assembly adapted to expel ions from said source and having a male socket element secured to the back thereof, ion producing means including a plate having threaded apertures therethrough, a plurality of adjusting screws threadably engaging said plate and bearing upon said plate assembly whereby the spacing between said plate assembly and said ion producing means is adjustable, said adjusting screws comprising a socket element engaging said plate assembly socket element whereby said plate assembly and said ion producing means may be disconnected without disturbing the setting of said adjusting screws, and locking means securing said ion producing means in position as determined by said adjusting screws.

6. In an ion source mechanism the combination comprising a plate assembly having ion accelerating and focusing plates, ion producing means including a filament plate and a filament secured to said plate at a predetermined distance therefrom, and spacing means connecting said ion producing means and said plate assembly, said spacing means including adjusting screws threadably engaging said filament plate and slidably engaging said plate assembly, thereby providing means for adjusting the spacing between said filament and said plate assembly and disconnecting said ion producing means from said plate assembly without disturbing said adjustment.

7. In an ion source mechanism the combination comprising a plate assembly adapted to expel ions from said ion source and including a plurality of prongs secured thereto and extend-

ing from the back thereof, ion producing means including a filament holder plate and a filament wire secured to said plate, adjusting means connecting said plate assembly and said ion producing means, said adjusting means comprising a plurality of adjusting screws threadably engaging said filament holder plate and each of said screws having a hole in the end thereof slidably engaging the prongs on said plate assembly in the manner of a socket connection whereby said filament may be adjusted with respect to the plate assembly and removed from said plate assembly without affecting said adjustment, and locking means comprising a plurality of bolts secured to said plate assembly and passing through said filament holder plate with cooperating nuts thereon whereby said filament may be firmly secured in position as determined by the setting of said adjusting screws.

20 8. In an ion source mechanism the combination comprising an ion source proper including a plate assembly adapted to expel ions from said ion source, and ion producing means removably spaced therefrom, said ion source proper having a male socket connection at one end thereof, an ion source box adapted to contain said ion source proper, said box enclosing a female socket connection slidably engaging the male socket connection on said ion source proper, an adjusting nut threadably engaging said female socket connection and bearing on said ion source proper thereby determining the position of said ion source proper within said box, and a locking nut threadably engaging said adjusting nut and bearing on said ion source proper whereby said ion source proper is secured in position as determined by said adjusting nut.

9. In an ion source mechanism the combination comprising a plate assembly adapted to expel ions from the ion source, ion producing means including a filament, adjusting means connecting said plate assembly and said ion producing means, said adjusting means defining the position of said filament with respect to said plate assembly and having a quick disconnect attachment whereby said filament may be removed from said plate assembly without affecting the setting of said adjusting means, a vacuum tight ion source box enclosing said plate assembly and ion producing means and having vacuum connections thereto, said box having an opening in one wall thereof and a hollow socket connection element disposed about said opening, said plate assembly comprising a socket connection element at the end opposite the ion producing means connection, said socket elements mating together to properly position said plate assembly in said ion source box, an adjusting nut threadably engaging said ion source box socket element and bearing upon said plate assembly, and a locking nut threadably engaging said adjusting nut and bearing upon said plate assembly whereby said plate assembly is secured in the position determined by said adjusting nut.

65 10. An ion source mechanism including the combination comprising three spaced plates disposed in parallel relationship with insulators therebetween, each of said plates having a slotted aperture in the center thereof in alignment, the 70 first of said plates having a filament disposed in the slot therein and spaced from the edges of the slot, current supply means connected across said filament whereby material disposed thereon is ionized, potential supply means impressing a large negative potential upon said

center plate with respect to said first plate and filament whereby ions formed at said filament are attracted therefrom in a stream through the aperture in said center plate, said potential supply means also impressing a negative potential upon said third plate whereby said stream of ions passing through the slot in said third plate is focused into a beam of small cross section.

11. An ion source mechanism as defined in claim 10 further characterized by a protection plate interposed between said first and center plates in parallel relation thereto and adjacent said center plate, means impressing substantially

the same potential on said protection plate as is impressed on said center plate whereby electrical current leakage between said first and center plates is prevented, and current measuring means connected between said first plate and said center plate in series with the power supply means therefor and thereby, measuring the current flow therebetween as an indication of the efficiency of said ion source.
